ROTARY INTERNAL-COMBUSTION ENGINE

Dove S. Jay, Detroit, Mich.

Application March 15, 1935, Serial No. 11,278

4 Claims. (Cl. 123—15)

This invention relates to rotary internal combustion engines.

Heretofore rotary engines have usually been driven by steam but it has long been recognized that if rotary engines of the internal combustion type could be satisfactorily made, they would lend themselves more readily to use in driving automobiles and airplanes, etc., as the rotary type would occupy comparatively less space than does the usual cylinder type of internal combustion engine, thus leaving more space to be devoted to utilitarian purposes. It was also thought that the rotary type would be freer from vibration than the other internal combustion types and would be more economical in operation. Consequently, many attempts have been made to make a satisfactory rotary engine of the internal combustion type. I am informed and believe that, on the whole, such attempts failed although some of them were more indicative of success than others. I am also informed and believe that the majority of the failures of the more successful attempts were due in the most part to the fact that the explosion chambers, were located in the rotor where it is difficult, and so far it has been impossible, to provide a satisfactory cooling system. For this reason I conceived the idea of locating the explosion chambers in the housing surrounding the rotor where they may be readily cooled in the usual manner and my invention embodies this idea.

The principal object of this invention lies in the provision of a rotary internal combustion type engine of simple construction and few moving parts which is driven by the force of explosions of fuel acting upon the cammed faces of grooves located in the rotor.

Another object of the invention lies in the provision of control valves actuated directly by cam surfaces on the rotor for controlling the intake of fuel into the combustion chamber and controlling the exhaust therefrom.

These and other objects and novel features of the invention will appear from the following description taken in connection with the accompanying drawings in which:

Fig. 1 is a cross sectional view of my rotary internal combustion type engine.

Fig. 2 is a sectional view taken on line 2—2 of Fig. 1.

Fig. 3 is a view in end elevation showing the valve operating mechanism.

Fig. 4 is a sectional view taken on line 4—4 of Fig. 2.

Fig. 5 is a diagrammatic view of the rotor and abutment valves.

In the accompanying drawings numeral 1 represents the motor driving shaft and 2 represents the rotor mounted thereon. Four semi-circumferential grooves are located on the rotor in staggered relationship as diagrammatically shown in Fig. 5. These grooves are designated by numerals 3, 4, 5, and 6. They are cam-shaped, having a quickly falling surface at one end and gradually rising to the outer circumference of the rotor at the other end, as may be clearly seen in Fig. 1. These grooves act as driving or firing cams as will be hereafter explained.

A circumferential housing 7 surrounds the rotor 15 and is provided with end plates 8 cooperating therewith in forming a complete housing for the rotor. Each end plate 8 carries a suitable bearing 9 surrounding the drive shaft 1.

A portion of the housing is enlarged to accommodate certain parts hereinafter to be described. I prefer to locate the enlarged part of the housing in the upper portion thereof, as clearly shown in Fig. 1.

In this enlarged portion of the housing I provide four explosion or combustion chambers of arcuate outline, 10, 11, 12, and 13, in which are respectively mounted abutment valves 14, 15, 16, and 17, rigidly secured to their respective rock shafts 18, 19, 20, and 21, as by keys or other well-known fastening means. These chambers are staggered in the same manner as the semi-circumferential grooves in the rotor, thus permitting the abutment valve of each chamber to drop only into its corresponding groove and causing said valve to ride on the offset portion of the rotor over the following groove.

The outermost end of each of said rock shafts extends through a bearing 21a extending through the end plates of the housing and the end of each such shaft has secured to it a vane member 22 enclosed in a circular chamber 23 formed by a closure or bracket member 24 secured to the end plates 8 of the housing.

In each of the chambers 23 there is located a stop member 25, see Fig. 4. This stop member serves a two-fold purpose. One side or face of it prevents its associated abutment valve from turning beyond a certain point in case of a break of the long arm or toe 28 of the abutment valves hereinafter to be described. The other side or rear face of the stop member acts as a seat for any type of spring means that may be mounted in the circular chamber to press the vane 22 in the direction of the first mentioned face of the

stop member, thus causing the said toe of the valve to follow the periphery of the rotor. For this purpose, I have shown a coiled spring 26 mounted in each of said circular chambers 23, having one end abutting against the rear face of the stop member and the other end abutting against one side of the vane 22.

The innermost end of each rock shaft terminates in a central bearing 27 located in the housing 1.

The abutment valves 14, 15, 16, and 17 are somewhat L shaped, having two arms, one arm preferably being longer than the other. The long arm of the abutment valve is herein designated 15 the toe 28 and the short arm is designated the heel 29. The contour of the explosion or combustion chambers is formed with an enlarged portion to accommodate the toe 28 of said abutment valves when not riding in their respective 20 grooves in the rotor.

The toe 28 of each of the said valves is adapted to prevent the passage of fuel from its associated combustion chamber into any of the rotor grooves when the toe is not riding in its respective groove 25 in the rotor.

By making the toe 28 of each abutment valve longer than the heel 29, a greater surface is provided on the toe than on the heel, thus, since pressure is equal and opposite in direction, any explosion that takes place in the explosion chambers will tend to force the toe 28 into its respective groove in the rotor, thereby aiding the springs 30 26 in operating the abutment valves. Thus the toe may be described as a follower or follower 35 arm, as it follows the periphery of the rotor, or as a contact arm as it continuously contacts the rotor.

Each of the explosion or combustion chambers 10, 11, 12, and 13 is provided with an intake port 40 31 and an exhaust port 33. Each intake port 31 is so located that, when the toe of the abutment valve located in its associated combustion chamber is not riding in its respective groove in the rotor, fuel may pass through the port 31 into 45 the combustion chamber, as clearly shown in the dotted line position of the abutment valves 16 and 17 shown in Fig. 1. The said dotted lines not only show the position of the abutment valves 14 and 15 when riding on the surface of the 50 rotor, but also show the position of the abutment valves 16 and 17 in the other two explosion chambers when toe 28 of abutment valve 14 is about to ride up on the surface of the rotor and toe 28 of abutment valve 15 has ridden down the 55 cam surface of its respective groove in the rotor.

The heel 29 of each of said abutment valves is of greater thickness than the toe and is arranged to close the exhaust port to its respective combustion chamber when its respective intake port 60 is open to said combustion chamber and vice versa.

This abutment valve and the inlet port and exhaust port construction permits fuel to enter each associated combustion chamber prior to the 65 time that the toe of its associated abutment valve drops into its respective groove in the rotor, at which time the usual ignition system (not shown) is timed to explode the charge, the pressure of the explosion acting upon the cammed groove in 70 the rotor and forcing the fly wheel to rotate; the exhaust of the previous explosion passes out through the groove, thence through the lower portion of the explosion chamber beneath the abutment valve and thence out the exhaust 75 port 33.

The fuel is fed to the motor under pressure by any suitable means (not shown) through valves communicating with the inlet ports of the respective explosion or combustion chambers. I have shown two oscillating valve units 37, each unit supplying gas or fuel alternately to two associated explosion chambers. Each oscillating valve unit comprises a stationary hollow casing 39 enclosing a hollow sleeve 41, said sleeve being oscillatable by a shaft 43 attached to and enclosing one end thereof. Each of said rock shafts 43 extends through a cap 45 threaded or otherwise secured to one end of the hollow casing 39.

Each of the said oscillatable valve sleeves 41 is provided with two discharge ports 47, spaced to register with the respective intake ports 31 leading to the respective explosion chambers associated therewith, and said oscillating valve discharge ports are adapted to open alternately first to the one and then to the other of said associated intake ports 31.

The end of each valve unit remote from the cap is open to receive fuel from the source of pressure supply through a passage 49, one to each oscillating valve unit.

Each of the valve rock shafts 43 is provided with its associated operating mechanism. Each such mechanism comprises an eccentric or cam member 51 mounted on the drive shaft 1, a supporting collar or band member 53 having a projecting member 55, a connecting rod 57 having one end secured to said projecting member, and a rocker arm 59, one end of which is pivotally connected to the other end of the connecting rod and the other end of which is fixedly secured to the 35 rock shaft 43.

Any suitable ignition system may be used. I have shown the usual spark plugs 61 mounted in chambers 63 registering with their respective explosion chambers.

The enlarged portion of the casing is suitably bored to provide for a water cooling system 65. The firing end of each driving cam or groove in the rotor is preferably provided with sealing means to prevent leakage of pressure or of explosive charge, etc. between the outer surface of the rotor and the inner surface of the housing. Preferably some expansible sealing means should be used. I have provided a pivotally mounted expansible sealing check 67 having a projecting 50 arm 69 which is adapted to be forced against the inner surface of the housing by the driving force of the explosion. This sealing means is of considerable benefit as it is advisable to make the outer diameter of the fly wheel smaller than the 55 bore of the housing so as to avoid excessive friction.

It will be seen that my rotary internal combustion engine comprises four explosion chambers which are arranged in the rotor housing to 60 cooperate with respective ones of four semi-circular grooves in the rotor. The grooves and chambers are arranged in staggered pairs so that the toe of the abutment valve in each combustion chamber is prevented from following the depressed surface of any other but its corresponding groove after which it rides up out of the groove onto the outer periphery of the rotor and does not enter the following groove. valve 14 riding up the inclined surface of groove 3 onto the outer periphery of the rotor, subsequent to the explosion of the chamber 10. In a diagrammatic view Fig. 5, the parts are shown 5 in the same position. In Fig. 1, I have also shown the parts in the approximate position that they will occupy when the gas in chamber 11 is exploding and this may also be seen in Fig. 5, it being remembered that the groove 4 is directly 10 adjacent or under chamber 11 at this time. Also in Fig. 1, the abutment valves 16 and 17, designated in dotted lines, are shown in the positions they would then occupy in chambers 12 and 13 since they are riding over the offset grooves at 15 this time, as shown in Fig. 5, due to the fact that toe 28 of valve 16 is only adapted to ride in groove 6 and toe 28 of valve 17 is only adapted to ride in groove 5. As the rotor revolves further to the left, toe 28 of valve 14 will ride over 20 but will not enter groove 4 and toe 28 of valve 15 will ride over but will not enter groove 3.

In Fig. 1, chamber 11 is shown with the heel 29 of abutment valve 15 having cut off the intake port 31 and having opened exhaust port 33 and 25 with the toe 28 of said valve having followed the depressed face of semi-circumferential groove 4, due to the action of the spring 26. As the force 30 of the explosion in this chamber turns the rotor further to the left, toe 28 of abutment valve 16, as shown by dotted lines in Fig. 1, will follow the depressed surface of groove 6 (see Fig. 5) and then an explosion will take place in chamber 13 (see Fig. 2) at exactly the same time that the 35 rotor has revolved ninety degrees counterclockwise from the position shown in Fig. 1. In like manner, an explosion will next take place in chamber 12, which is under the chamber 10 shown in Fig. 1, and then in chamber 10, two explosions taking place simultaneously each half 40 turn of the rotor, and only one explosion taking place in each chamber on each complete revolution of the rotor.

Aside from the specific embodiment of the invention herein shown and described, it will be 45 understood that numerous details of the construction may be altered or omitted without departing from the spirit and scope of the invention as disclosed and claimed, and that I do not desire to limit the invention to the exact construction 50 herein set forth.

I claim:

1. In a rotary internal combustion engine, in combination, a housing having an opening therethrough, a rotor rotatably mounted in said opening and having two pairs of opposed and staggered recessed portions therein, two pairs of opposed combustion chambers positioned in said housing and opening into said rotor opening, each combustion chamber having an inlet conduit and an 55 exhaust conduit, valves communicating with the inlet conduits and adapted to open thereto in series sequence, a pivoted lever mounted in each 60 of said combustion chambers, each lever having two arms, one arm of each lever being longer than 65 the other and being adapted to move into and out of its respective recessed portion of said rotor,

the other arm of each lever acting as a closing means to close either said intake or exhaust conduit in its respective combustion chamber and means for pressing the longer arm of each lever toward the rotor.

2. In combination in a rotary internal combustion engine, a housing having a substantially cylindrical opening therein, a rotor of suitable conformation for rotating therein, bearing means for journaling said rotor in said opening, a plurality of combustion chambers in said housing connecting through the side walls of said rotor receiving opening, a plurality of grooves recessed circumferentially in the peripheral surface of said rotor, ports connecting from and to each of said chambers, a valve pivotally mounted in each of said chambers for controlling the flow of gas to and from the respective ports, a valve actuating member projecting from each valve for actuating the same in accordance with the bottom contour 10 of a corresponding one of said grooves, and said chambers, valves and grooves being offset axially in staggered relation so that, as the rotor rotates, each valve actuating member enters only a corresponding one of the grooves and passes freely 15 over all the other grooves.

3. In a rotary internal combustion engine, in combination, a housing having an opening therethrough, a rotor having recesses therein rotatably mounted in said opening, opposed combustion 20 chambers in said housing and opening into said rotor opening, each of said combustion chambers having an inlet conduit leading through the side wall and an exhaust conduit leading therethrough, and an abutment valve mounted in each combustion chamber, each valve having a long arm adapted 25 to contact the periphery of the rotor and a thick heel actuated by contact of said contact arm with the rotor and adapted to engage the side wall of each chamber to alternately close 30 the respective inlet and outlet conduits of the combustion chamber in which it is located.

4. In a rotary internal combustion engine, in combination, a housing having an opening therethrough, a rotor having recessed portions therein 45 rotatably mounted in said opening, said recessed portions being axially staggered, opposed combustion chambers positioned in said housing and opening into said rotor opening, a pair of valves mounted on said housing, intake conduits connecting from said valves through the side walls of said combustion chambers and exhaust conduits leading through the side walls of said combustion chambers, closing means in said chambers for said intake and exhaust conduits, said closing 50 means comprising pivoted levers each having two arms, one of said levers being mounted in each combustion chamber, one arm of each lever acting as a follower and suitably disposed axially for contacting the corresponding recessed portion of 55 said rotor, and the other arm of each lever comprising a thick flow restricting heel engaging the side wall of its chamber and acting as a closing means to close either said intake or exhaust conduits.

DOVE S. JAY.
